CLAIM

The ornamental design for a charging base for a portable media playback device as shown and described.

DESCRIPTION

FIG. 1 is a front elevation view of a charging base for a portable media playback device.

FIG. 2 is a rear elevation view thereof.

FIG. 3 is a top plan view thereof.

FIG. 4 is a bottom plan view thereof.

FIG. 5 is a left side view thereof.

FIG. 6 is a right side view thereof.

FIG. 7 is a perspective view thereof; and,

FIG. 8 is another perspective view thereof.

The dashed broken lines in the figures illustrate portions of the charging base for a portable media playback device that form no part of the claimed design. The wavy dashed broken lines illustrate a symbolic break shown in the length of the cable of a charging base for a portable media playback device. The appearance of any portion of the article between the break lines forms no part of the claimed design.
